UNITED STATES PATENT OFFICE.

AMANDUS A. CARLSON, OF BARNESVILLE, MINNESOTA.

BAG-RACK.

1,313,257.

Specification of Letters Patent.

Patented Aug. 19, 1919.

Application filed January 7, 1919. Serial No. 270,020.

To all whom it may concern:

Be it known that I, AMANDUS A. CARLSON, a citizen of the United States, residing at Barnesville, in the county of Clay and State of Minnesota, have invented certain new and useful Improvements in Bag-Racks, of which the following is a specification.

This invention is a bag rack and has for its principal object the production of an efficient means for holding bags of various sizes in position, whereby the same may be readily removed for use, when desired.

Another object of this invention is the production of a bag rack wherein a plurality of supporting elements are employed for supporting bags of various sizes, thus preventing the bags from becoming confused, whereby a bag of desired size may be readily removed from the rack.

20 Another object of this invention is the production of a bag rack wherein the supporting frames are hingedly carried by the casing, whereby the bags may be readily removed as desired.

25 Another object of this invention is the production of a bag rack wherein the supporting frames carried by the casing are so arranged as to overlap the ends of the bag, thus holding the same against displacement, 30 although permitting the bags to be easily gripped and pulled from engagement with the rack as desired.

One practical form of construction and assembly of the present invention will be 35 hereinafter described and is illustrated in the accompanying drawing, in which—

Figure 1 is a front elevation of the bag rack.

Fig. 2 is a vertical sectional view through 40 the bag rack, and

Fig. 3 is a detail perspective view of one of the supporting frames.

In the preferred embodiment of the present invention about to be described, it will 45 be seen that the main casing is indicated in general at 5. This casing 5 consists of a base 6 having side walls 7 extending upwardly therefrom and parallel to each other. The side walls 7 have a top 8 mounted thereon, as shown in Figs. 1 and 2. The back 9 is supported upon the base 6 and engages the inner surfaces of the side walls 7 and the top 8. This back 9 slants rearwardly toward its upper end, as shown clearly in 50 Fig. 2 and it will be noted that the lower end of this back is reinforced by a cleat 10

carried upon the base 6, whereby the supporting strain imparted to the back will not displace the same and it will be further noted that owing to the slant of the back, 60 the frames will be so carried as to relieve the necessity for secondary supporting means for holding the rack upon a counter or in any other desired position without danger of the same overturning. 65

Each supporting frame comprises a back 11 having a bottom 12 supported thereon. 68 The guide flanges 13 are connected to the back 11 and to the bottom 12 while the front flange 14 is also connected to the bottom 12 70 and to the end flanges 13. Therefore, it is obvious that bags positioned upon the shelf 72 will be held from slipping from the frame as the same is being swung or moved. A strip 15 is carried upon the rear surface of the 75 back 11 at the upper end thereof and thus holds flexible straps 16 upon the back 11. 80 The supporting frames are similarly constructed, the only difference being in the various sizes, for accommodating bags of 85 various sizes. The supporting frames are positioned within the casing 5, as shown in Figs. 1 and 2 and at this time the straps 16 are fixed to the back 9 or to any other element within the casing, for hingedly supporting the frames.

It will be noted that the casing is divided by a division wall 7' which is similar in construction to the side walls 7. It will be noted that the division wall 7' is carried off-center with respect to the center portion of the casing 5 and for this reason permits larger supporting frames to be carried upon one side thereof than upon the other side, as shown in Fig. 1. 95

Coiled springs 17 are fixed upon the upper surface of the top 8 and have retaining loops 18 extending downwardly therefrom. These retaining loops are positioned to engage the back 11 of the upper supporting 100 frame upon each side of the division wall 9. It will also be noted that the casing 5 is provided with a retaining flange 19, carried by the base 6 and the side walls 7, as shown in Figs. 1 and 2. 105

When the device is in operation, it is in condition to receive bags as originally packed. Under such conditions, as is well known, the bags have the lower portions thereof folded to form flaps. The bags coming in bundles are arranged within the casing. The larger sized bags are carried upon

the base 6 upon one side of the division wall 7' and the next larger bag is positioned upon the largest supporting frame directly above the portion of the base carrying the largest bags. The last referred to bags will have their upper ends fitting behind the supporting frame directly thereabove and the bags of a smaller size are positioned upon the opposite side of the division wall in the same manner. As above explained, it will be noted that the upper portion of the bags will be held against displacement by the lower portion of the supporting frames thereabove resting thereon.

15 It is necessary to hold the bags in position upon the top supporting frames and for this reason the coiled springs 17 having the loops 18 are provided. The loops may be swung outwardly against the tension of the 20 coiled springs and the bags positioned upon the upper supporting frames and then the loops may be released, thus allowing the springs to bring the loops into binding engagement with the bags. Thus the bags 25 upon the top supporting frames will be positively held against accidental displacement.

Since the retaining frames and the base of the casing are provided with front flanges 30 14 and 19 and also with side flanges 13 and side walls 7, it will be seen that the bags will also be held against side displacement.

When however, it is desired to use one of the bags, the flap thereof may be gripped 35 and pulled outwardly, thus pulling the bag from engagement with its particular supporting frame. As hereinbefore explained, the supporting frames will be bearing upon the bags, but in view of the fact that these 40 supporting frames are hingedly supported, it is obvious the bags may be easily pulled from engagement with the rack when desired for use. The same action occurs when a bag is pulled from engagement with the 45 springs.

From the foregoing description it will be seen that a very simple and efficient bag rack has been produced, wherein various sized bags may be easily supported thereon and 50 held against displacement, although they may be easily pulled from engagement with the rack when it is desired to use the same.

Furthermore, it will be noted that the supporting frames not only support the bags placed thereon, but also engage the upper portion of the bag carried by the frame therebelow or on the base and thus hold these bags against displacement.

55 The foregoing description and the drawings have reference to what may be considered the preferred, or approved, form of my invention. It is to be understood that I may make such changes in construction and arrangement and combination of parts, materials, dimensions, et cetera, as may prove expedient and fall within the scope 60 of the appended claim.

Having thus fully described my invention, what I claim as new and desire to secure by Letters Patent, is:—

70 In a device of the character described, the combination of a main casing including a supporting wall which is inclined rearwardly toward its upper end, bag supporting frames carried within said casing, each frame being formed of a rectangular unobstructed back, a bottom fixed at the lower end of said back and extending at right angles thereto, a flange extending longitudinally of said bottom and parallel to said back, flanges connected to the ends of said flange and to the lower side edges of said back, whereby the side edges of the back above said flanges are unobstructed, thus 75 allowing access to the bags carried upon the bottom, said flanges holding the bags against side displacement, said supporting frames being positioned respectively one in front of the other toward the upper portion of the casing, the upper ends of said backs being hingedly mounted upon said walls, the back of one frame bearing upon the front of the back of the frame therebelow owing to the angle of inclination of said wall, thus 80 causing the upper supporting frame to bear 85 upon any thickness of bags carried by the supporting frames to hold the same against 90 displacement.

95 In testimony whereof I affix my signature in presence of two witnesses.

AMANDUS A. CARLSON.
